FISHERMAN'S BARREL KNOT TIER

Filed Feb. 21, 1947

UNITED STATES PATENT OFFICE

2,469,037

FISHERMAN'S BARREL KNOT TIER

James W. Harvey, Lakeville, Conn.

Application February 21, 1947, Serial No. 730,153

12 Claims. (Cl. 289—17)

1

My invention relates to means for tying what are commonly called "barrel" knots such as are used to tie together strands of natural or artificial gut for forming fish line leaders, and this application is a partial continuation of my application #713,478, filed December 2, 1946.

The present application is intended to cover a simple form of apparatus, which can be carried and used by amateur fishermen, and others, either at home or in the field.

In the form shown, a base plate is provided with means for mounting two supports for gripping the strands to be united and a central holder for twisting the strands and having grippers for holding the tips of the strands and drawing them through the twisted strands when tying the knot.

Fig. 1 is a perspective view of one form of device involving my invention showing the ends of two strands to be connected.

Fig. 2 is a transverse sectional view showing the mounting of one of the strand supports.

Fig. 3 is a transverse sectional view showing the mounting of the central strand holder.

Figs. 4, 5 and 6 are front views showing successive stages of the tying action.

Fig. 7 is an enlarged view showing a barrel knot as tied on this device before the ends are clipped off.

Fig. 8 is a detail perspective view of a modified form of strand gripping support.

In the simplest form the device has a base plate 10 with two strand gripping supports 11 and 12, spaced apart from each other and a central strand holding member 13 between them. Each support has a central post 14, and two spring jaws 15, 15 secured to the opposite sides of the post 14 by a rivet 16. Each support is preferably demountably secured to the base by mounting it in a resilient bushing 17 in the base. A recess 18 in the lower face of the base accommodates the feet 19, 19 of the side jaw members 15, 15.

The central holding member 13 consists of a central post 20 and spring jaws 21, 21 secured to its opposite sides by a rivet 22. The base is provided with a resilient socket or bushing 23 for the holding member 13. This socket is fixed in a recess 24 in the base and serves to frictionally hold the member 13 when the knot is being completed. When tying a knot the base plate is held stationary.

To join two strands by a barrel knot the two strands are first inserted into the supports 11 and 12. For instance, the main part of strand 25 is

2

slipped between post 14 and one of the jaws 15 of support 11 and similarly is secured to post 12 leaving its tip 26 extending beyond it to the right. Strand 27 is then mounted in posts 12 and 11 in the similar manner leaving its tip 28 extending to the left of support 11.

The central holder 13 is then inserted between the strands and turned so as to twist the strands 3 or 4 times. This central holder 13 thus constitutes a twisting member or means for twisting the strands which are held by the supports 11 and 12. Preferably the supports 11 and 12 are mounted in resilient bushings 17 so that the supports can yield toward each other as the strands are twisted 15—thus avoiding slippage of the strands as they are twisted and consequent possible chafing of the strands. After twisting the strands the lower end of the holder 13 is inserted in the socket 23.

The tips 26 and 28 are then withdrawn from 20 the supports 12 and 11, respectively, and tucked between the central post 20 and the spring jaws 21, 21 as shown in Fig. 4.

The supports and holding members are preferably formed of strips of resilient non-corrodible 25 metal and the tips of the jaws 15 and 21 are preferably rounded off and spread or bent outwardly to facilitate the insertion of the strands alongside of the posts 14 and 20, respectively.

After the tips of the strands have been secured 30 to the central member 13 the main parts of the strands are released from the supports 11 and 12 and pulled outwardly as shown in Fig. 5, so as to retract the twisted strands from the center member 13 and the tips 26 and 28. The tips 26 and 28 are then released from the jaws of the holder and strands 25 and 27 are drawn apart as shown in Fig. 6.

The strands are then pulled away from each other so as to form the knot by drawing the 40 turns of the strands tightly together as shown in Fig. 7.

The tips are then cut off close to the knot unless a tippet is desired, in which case only one of the tips would ordinarily be cut off.

45 When not in use the supports 11 and 12 and the holder 13 can be conveniently stored in the pockets 29, 29 and 30, respectively, which extend transversely of the base plate. (See Fig. 1.)

An alternative form of the support 11 is shown 50 in Fig. 8. In this case the support 11' consists of a rubber member slotted at 31, 31 to form a central member 14' with the two resilient gripping jaws 15', 15' for holding the strands to be joined in the same manner as above described.

I claim:

1. A knot tyer comprising a base plate, two spaced-apart supports projecting therefrom, each having a central post and two parallel resilient jaw members for holding strands to be twisted and a holding member between said supports having a central post and two spaced gripping jaws for holding the tips of the twisted strands while the remainder of said twisted strands are released from said supports and pulled so as to disengage the twisted strands from said holding member and permit the tips of the strands to be drawn through the twisted parts of the strands preparatory to pulling the knot tight.
2. A knot tyer comprising a base plate, two supports projecting therefrom, each having a central post and two resilient jaw members for holding strands to be twisted and a holding member by which the strands can be twisted between said supports, means for detachably securing said holding member and said base plate, said holding member having gripping jaws for holding the tips of the twisted strands while the remainder of said twisted strands are released from said supports and pulled so as to disengage the twisted strands from said holding member and permit the tips of the strands to be drawn through the twisted parts of the strands preparatory to pulling the knot tight.
3. A knot tyer comprising a perforated base plate having two supports extending through openings therein and having feet spread beneath the base plate and a holder supported between said supports, each of said supports having two spring fingers detachably supported in the base plate.
4. A knot tyer comprising a base plate, a strand gripping support at each end of said plate, a holder for insertion between and twisting strands held by said supports, means for supporting said holder on the base plate, said holder having means for holding the tips of the twisted strands while the strands are released from the supports, each support comprising a central post and two spring strips secured to the post.
5. A knot tyer comprising a flat base plate having three recesses extending at right angles to the plane of said plate and three pockets extending parallel to said plane, two supports each having two spring jaws and interchangeably fitting two of said recesses and two of said pockets and a holder having two spring jaws interchangeably fitting the third recess and the third pocket.
6. A knot tyer comprising a base plate, two supports having strand gripping jaws, means for resiliently mounting said supports spaced-apart from each other in said base plate to permit said supports to yield toward and from each other, means for twisting strands held by said supports and means for holding the tips of strands between said supports.
7. A tyer for barrel knots comprising a base plate having three rubber bushings spaced-apart from each other in a row and a strand holding member mounted in each bushing, each member consisting of three metal strips constituting a central post and two strand gripping jaws.
8. The method of forming a barrel knot connecting the ends of two strands which comprises first holding the two strands with their ends overlapping, then twisting the strands together relatively about a central holder, then gripping the tip ends of the strands to the holder, then pulling the twisted strands from the holder and draw-

ing the tip ends of the strands between the twisted parts of the strands and then pulling the strands in opposite directions and drawing the twisted turns together.

- 5 9. The method of forming a barrel knot to connect the ends of two strands which comprises first holding the two strands with their ends overlapping, inserting a holder between the strands and turning it to twist the strands together about 10 the holder, then gripping the free ends of the strands to the holder, then pulling the twisted strands from the holder and drawing the ends of the strands between the twisted parts of the strands and then pulling the strands in opposite 15 directions and drawing the twisted turns together.
- 10 10. A barrel knot tying device comprising a base, two supports secured to the base at positions spaced apart and each having a central post and two spring jaws for detachably holding 20 parts of two overlapping strands side-by-side and a twister holder adapted to be inserted between the strands held between said posts and adapted to twist said strands and means for 25 detachably securing said twister holder to the base between said posts after the strands have been twisted, said twister holder having means for detachably gripping the tip ends of the two twisted strands while other parts of the respective 30 strands are held by said supports.
- 11 11. In a barrel knot tying device, a base plate, two supports secured to said plate spaced apart from each other, each support having means for holding two overlapping strands to be tied and 35 a holding member adapted to be inserted between the strands held by the supports for twisting the strands between the supports and about said holding member and means for detachably mounting said holding member in said base between said 40 supports, said holding member having means for holding the ends of the two twisted strands after the ends of the strands are transferred from the supporting jaws and while the remaining portions of the twisted strands are disengaged from the supports and pulled so as to disengage the twisted strands from the holding member.
- 12 12. Apparatus for tying barrel knots comprising a base having two holes spaced apart from each other for receiving strand gripping supports and a recess between the holes constituting a socket to receive a twisting member, a strand gripping support inserted in each hole, each support consisting of a central post and a spring jaw secured to each side of said post and a 55 twisting holder insertable between overlapping strands held by the strand gripping support for twisting such strands and insertable into said recess in the base, said holder consisting of a central post with a spring jaw secured on each side thereof.
